UNITED STATES PATENT OFFICE.

DANIEL R. Houser, of LANCASTER, PENNSYLVANIA, ASSIGNOR TO JAMES ROSE, OF LANCASTER, PENNSYLVANIA.

FABRIC FOR UMBRELLA-COVERS.

1,074,053.

Specification of Letters Patent. Patented Sept. 23, 1913.

Application filed September 7, 1911. Serial No. 648,039.

To all whom it may concern:

Be it known that I, DANIEL R. Houser, a citizen of the United States, residing at Lancaster, in the county of Lancaster and State of Pennsylvania, have invented certain new and useful Improvements in Fabric for Umbrella-Covers, of which the following is a specification.

This invention relates to woven textile fabrics for use as umbrella covers.

The essentials of a fabric for umbrella covers are, first, that it shall be strong and durable throughout, shall be capable of withstanding the strain on the weft or filling incident to its attachment to the frame of an umbrella and to continued strain when the umbrella is raised; and further that that portion of the fabric which in a completed umbrella cover constitutes the edge shall be reinforced in respect of the warp in order that it may withstand the sudden strain placed upon it in raising an umbrella and the continuing strain to which it is subjected during the whole time an umbrella is raised, it being necessary in order to meet the requirements that when an umbrella is raised the entire covering be under tension in order to present the desired and universally required appearance. The strength necessary at the edge of the cloth has usually been given either by hemming or by forming a selvage edge on it. Hemming involves a large and needless expense and is not as presentable as a selvage edge and therefore the latter is most used for the purpose. When in a fabric of which the warp is of silk, the edge is thickened in order to strengthen it by increasing the number or size of the silk threads of the warp a great increase in the cost of the material results, and as the silk is neither strong nor durable it quickly breaks or wears out in use. In order to meet the requirements of cloth for umbrellas of higher grades it must have more or less luster, and in all cases the fabric used for covers must be as thin as practicable in order not to present a bulky appearance when the umbrella is folded or rolled. The most available way to obtain these ends is by the use of silk in the fabric.

The object of my invention is to produce a fabric which shall be cheap and shall meet all the requirements of lightness,

strength and appearance, and which by its peculiar formation shall not only present the required strength to withstand strain in the direction in which it is most imposed in attaching it to an umbrella frame and when an umbrella is raised, but which shall be possessed of additional strength in the part which when the fabric is used as an umbrella cover forms the edge thereof.

With this object in view the invention consists essentially of a fabric for the purpose described wherein the warp is composed principally of light, preferably lustrous threads, the weft is of strong threads or yarns preferably cotton yarns, and the selvage edges are formed by arranging stronger threads or yarns for the required width at each side of the lighter threads constituting the principal part of the warp, with which are woven the stronger threads or yarns constituting the weft or filling.

In the accompanying drawing Figure 1 represents a length of cloth made in accordance with my invention, on which are indicated by dotted lines the cuts which are made to form sections of umbrella covers; Fig. 2 represents a section of cloth cut from the strip and designed to form a portion of an umbrella cover; Fig. 3 is a view showing the form assumed by the section when it is joined to other corresponding sections at its edges, and when it is attached to a notch ring and is stretched and attached to the ends of umbrella ribs; Fig. 4 is a side view of a completed umbrella of which the improved fabric forms the cover; and Fig. 5 is a view on an enlarged scale of a portion of the fabric shown on Fig. 1.

In weaving the cloth the warp 1 is arranged in a loom of ordinary construction, the number of warp threads utilized in the body of the cloth being governed by the quality of cloth to be produced. The warp preferably employed by me is of silk threads of a number which when woven with a weft or filling of other, non-lustrous, material such as cotton will impart a distinct luster, to the completed fabric. On each side of the warp threads forming the principal part of the warp are arranged threads or yarn 2 which are stronger or larger or more closely grouped than those forming the body of the warp. They are preferably of mercerized cotton or similar strong inexpensive

material and of a number per inch, which is larger than that of the silk threads of the body of the warp employed.

The weft threads employed are of some 5 cheap material preferably for purposes of strength being of cotton yarn. In the weaving of the cloth the body 3 thereof is preferably woven thread for thread of warp and weft in order to present a smooth uniform appearance, but the selvage edge 4 may be woven in any suitable way to give any desired appearance to the edge of the cloth, as for instance the edge may be woven to give the appearance of ottoman silk, the warp 10 threads to overlie any number of the weft threads to present ribs of the desired width. The ribs so formed may extend either at right angles to the edge of the fabric, or 15 at any other angle thereto.

20 Triangular sections are cut as indicated by the dotted lines in Fig. 1 across the fabric woven as described, and the smaller ends of the sections are placed in contact and the edges of the sections sewn together throughout the entire length, to form umbrella covers. The width of the fabric is normally shorter than the length of the umbrella ribs to which the cover is to be attached. In 25 attaching a cover to a frame the upper portion is first secured to the notch ring of the umbrella and the material is then tightly drawn and stretched and sewn to the outer ends of the ribs. The strain thus imposed is necessary in order to give a taut appearance to the cloth, in the finished article, and this whole strain comes upon the weft or 30 filling of the material. When the cover made as described is connected by thread or other means of attaching it to the ends of the ribs the thread passes through the outer 35 edge of the cloth, and the necessity for

strength at this point both for purposes of withstanding the strain of the attaching thread and of the tensile strain imposed upon the edge when the umbrella is raised, 45 is apparent.

A fabric formed as herein described is superior in point of strength, where this is most required, to anything heretofore made for the purpose, its appearance when 50 composed of a silk warp and a cotton weft is similar to silk, and by reason of forming the thickened edge entirely of cotton that part is given the necessary strength and wearing quality, and the cost of the fabric 55 is less than if the edge be strengthened in any other way.

Having thus described my invention, what I claim as new, and desire to secure by Letters Patent, is:—

1. As a new article of manufacture a fabric for umbrella covering the body of which is composed of silk warp threads and cotton weft yarns interwoven with the warp threads, the edges of the fabric being composed of cotton warp yarns interwoven with the weft yarns.

2. As a new article of manufacture a fabric for umbrella covering the body of the warp of which is composed of thin silk 70 warp threads, the edges of the warp being of cotton warp yarns coarser than the silk threads, and a weft or filling of cotton yarn interwoven with the warp formed as described.

—In testimony whereof I affix my signature in presence of two witnesses.

DANIEL R. HOUSER.
